UNITED STATES PATENT OFFICE.

HENRY MOECKER, JR., OF HOMewood, AND THEODORE THOMPSON AND OTTO HAMMERMEISTER, OF HARVEY, ILLINOIS, ASSIGNORS TO AMERICAN STOVE COMPANY, OF ST. LOUIS, MISSOURI, A CORPORATION OF NEW JERSEY.

HINGE.

Application filed December 18, 1924. Serial No. 756,772.

To all whom it may concern:

Be it known that we, HENRY MOECKER, Jr., THEODORE THOMPSON, and OTTO HAMMERMEISTER, all citizens of the United States, residing at Homewood and Harvey, respectively, in the county of Cook and State of Illinois, have invented new and useful Improvements in Hinges, of which the following is a specification, reference being had

10 therein to the accompanying drawings.

This invention relates to improvements in hinges pertaining more particularly to a hinge and hinge housing for use upon drop doors as applied to stove ovens.

15 One of the objects of the invention is to provide a spring hinge and hinge casing construction wherein the tension of the spring is easily and quickly adjustable.

Another object of the invention is to provide a spring hinge the tension of which is adjustable and at the same time provide a construction which is strong yet simple and cheap of manufacture and highly efficient in operation.

25 A still further object of the invention is to provide a novel form of hinge and hinge casing construction which can be fastened to the stove frame by the use of only one bolt or screw.

30 A still further object of the invention is to provide a spring hinge construction wherein the spring is applied to the trunnion of the hinge in a novel manner to permit the ready and easy adjustment of the spring tension.

35 Another and further object of the invention is to provide a spring hinge construction and casing therefor composed of a minimum number of parts.

Other objects, novel features of construction and improved results of the device will appear in the following description and accompanying drawings.

In the drawings:

Figure 1 is a view in front elevation of one corner of an oven door showing the improved hinge construction applied thereto.

Figure 2 is an enlarged detail perspective

view of the parts comprising the hinge and casing, the parts being shown in extended unassembled relation.

50

In the manufacture of stoves it is desirable in respect to the hinges of the oven doors that the hinges be of as simple a construction as possible but at the same time provide a hinge of sturdy character so that it will stand long and hard usage. Additionally it is desirable that these hinges be spring hinges so that when the doors are in an open position and released they will automatically close themselves. Furthermore the hinges should not detract unnecessarily from the appearance of the stoves by being attached by numerous bolts, screws or the like.

55

Having the above enumerated facts in mind the present invention has been conceived and although the drawings show and the description describes the hinge as being attached to stove oven doors it will be readily understood that the construction could be utilized in respect to doors of other characters.

60

Referring now to the drawings, A represents the front frame of the stove oven, B the oven door, C the oven hinge, D the hinge pintle or trunnion, E the hinge spring, F the hinge casing, or trunnion housing, and G the hinge or door stop.

65

Describing the invention more specifically it will be seen that the hinge C comprises a vertical leg 1 and a horizontal leg 2 joined to form an L shaped bracket. The jointure of the horizontal and vertical legs is bulged out as at 3 to add to the strength of and the appearance of the bracket. It will be readily understood that the hinge C can be cast in one piece. The back of the vertical and horizontal legs of the hinge are provided at their outer edges with flanges 4 and 5 while centrally positioned at several points throughout the length of the two members are screw-threaded holes or openings 6.

70

It will be seen that the hinge member C will fit the corner of a door and support and hold the door between the flanges 4 and 5.

75

The hinge can be fastened securely to the door by means of suitable screws (not shown) which will enter the threaded openings 6 of the hinge.

- 5 Cast integrally with the hinge C and extending downwardly and outwardly therefrom is an enlarged portion 7. The lower front face of the portion 7 is flat as at 8 and is provided with a slight extension 9. The 10 purpose of the flat face 8 and extension 9 will be hereinafter described.

Extending outwardly from the enlarged portion 7 of the hinge is the circular pintle or trunnion D. Positioned in a plane about 15 the inner end of the trunnion or pintle D in the end of the enlarged portion 7 are a series of openings designated by the numerals 10, 11 and 12.

The spring for the hinge is designated by 20 the letter E and as clearly appears in the drawings is a coil or spiral spring the end 13 of which extends outwardly in a horizontal plane from the coil while the other end 14 of the spring extends upwardly in a 25 vertical plane from the coil.

The spring casing or trunnion housing is designated by the letter F and comprises a housing having a closed end 15 provided with an opening or aperture 16 adapted to 30 rotatably support the outer end 17 of the hinge pintle. Additionally it will be seen that this opening 16 is centrally located in that portion 15 of the housing which closes the enlarged portion 18 of this member. 35 The inner side of enlarged housing portion 18 is open as at 19. With this construction it will be seen that the coil spring E is carried within the enlarged portion 18 of the housing.

40 As clearly appears in Figure 1 of the drawings the end 13 of the spring is inserted in one of the openings 10, 11 or 12 while the vertical end 14 of the spring engages the portion 20 of the casing F.

45 The casing F is additionally provided with the door or hinge stop G which comprises an extension adapted in the assembled hinge to be in a position below or slightly separated from the enlarged portion 50 7 of the hinge C.

The casing F is fastened to the door by means of a screw or bolt 21 which penetrates the opening 22 in the upper end 23 of the casing. This is the only bolt or screw used

55 to fasten the casing in place. The lower end of the casing is prevented from shifting about upon the stove frame by reason of the pin 24 which is cast with and carried by the rear face of the hinge or door stop G.

60 This pin 24 is adapted to enter and engage a drilled hole in the front of the stove frame.

An assembled view of the parts composing the invention appears in Figure 1 of the 65 drawings. It will be seen that the hinge

is fastened to the door in a manner whereby no screw or bolt heads are in evidence. Furthermore the hinge casing is fastened to the stove frame by the use of only one bolt or screw and is held against shifting 70 movement through the medium of the pin 24 which in addition to functioning in this manner adds strength to the hinge or door stop G. Additionally by fastening the hinge casing in this manner a certain amount of 75 flexibility is given to the mounting of the casing.

It will be seen that through the medium of the openings 10, 11 and 12 the tension of the spring can be easily and quickly 80 changed. Furthermore the openings 10, 11 and 12 are in the strong part of the hinge and therefore do not weaken the construction. Irrespective of what tension the spring is adjusted to the vertical end 14 of 85 the spring will engage the part 20 of the casing.

Furthermore it will be seen that when the door is swung to an open position the projection 9 of the lower face 8 of the hinge 90 portion 7 will engage the door stop G of the casing and prevent the operator from opening the door beyond this point.

Attention is further directed to the fact that the hinge casing or housing F bears 95 directly against the front of the oven frame thereby making the device unusually strong and solid and overcomes any chance of the device being broken or damaged by the operator opening the door violently against 100 the door stop G.

Attention is directed to the fact that the rear face of the upper end 23 of the casing F is provided with flanged edges and that a flange surrounds the inner edge of the bolt opening 22. By this construction the casing will rest flush against the frame A of the stove even though the vertical extending end 14 of the coil spring E is positioned between the casing and the stove frame. In 110 other words due to this construction the portion 20 of the casing is in reality a depression which is at least as great in depth as the thickness of the end 14 of the coil spring.

Having thus described our invention what we claim and desire to secure by Letters Patent is:

1. In a spring hinge construction, a hinge member provided with a pintle, a coil spring carried upon and surrounding said pintle, a casing adapted to receive and support said pintle, the hinge member provided with a series of openings adjacent one end of said pintle, and the coil spring provided with an extending end adapted for selective engagement with said openings.

2. In a spring hinge construction, a hinge member provided with a pintle, a coil spring surrounding said pintle, a casing adapted

to receive and support said pintle, the hinge member provided with an enlarged portion adjacent one end of said pintle, said enlarged portion provided with a series of openings, and the coil spring provided with an extending end adapted for selective engagement with said openings.

3. In a hinge construction, a hinge member provided with a pintle, a coil spring surrounding said pintle, a casing adapted to receive and support said pintle, said casing adapted to be fastened to a door frame by means of a bolt at its upper end and an inwardly extending lug at its lower end.

15 4. In a spring hinge construction, a hinge member provided with a pintle, a coil spring surrounding said pintle and having one extending end in a horizontal plane and its opposite end extending in a vertical plane,

20 a casing adapted to receive and support said pintle, the hinge member provided with openings adjacent one end of the pintle, the horizontal extending end of the spring adapted for selective engagement with the hinge member openings, and the vertical extending end of the spring adapted to engage the inner face of the casing, whereby the tension of the spring is adjustable.

5. In a hinge construction, a hinge member provided with a pintle, a casing adapted to receive and support said pintle, the casing provided at its lower end with an inwardly extending stop, the hinge member provided with an extending portion having a flat face, whereby the flat face of the hinge member is adapted to engage the stop of the casing upon the rotation of the hinge member.

6. In a spring hinge construction, a hinge member provided with a pintle, a coil spring surrounding said pintle, a hinge casing adapted to receive and support said pintle and spring, the outer end of said pintle extending through an opening in the end wall of said casing, the hinge member provided with an enlarged portion adjacent the inner end of said pintle, the side of said enlarged portion provided with a series of openings adjacent the end of the pintle and the lower face of said enlarged portion flattened and extending outwardly beyond the hinge member, one end of said spring adapted for selective engagement with said hinge member openings and the other end of the spring adapted for engagement with the casing, and the lower end of said casing provided with an inwardly extending stop member adapted for engagement with the outwardly extending flattened portion of the enlarged portion of the hinge member.

7. In a hinge casing adapted to receive and rotatably support a hinge pintle, a bolt for fastening the upper end of said casing to a door frame or the like, and the lower end of said casing provided with an in-

wardly extending pin adapted for engagement with an opening in said frame, whereby said casing is fastened to the frame to withstand both vertical and horizontal pressure by the use of one bolt.

8. In a spring construction, a hinge member provided with a pintle, a coil spring surrounding said pintle, a casing adapted to receive and support said pintle, the hinge member provided with openings adjacent one end of the pintle, one end of the spring adapted for selective engagement with said openings, and the other end of said spring adapted for engagement with a depressed portion in the rear wall of said casing, whereby the tension of the spring is adjustable and the casing is permitted to rest flush upon the member to which it is fastened.

15 9. In a hinge construction, a hinge member provided with a pintle, a coil spring carried upon and surrounding said pintle, a casing adapted to receive and support said pintle, the lower end of the hinge member adjacent its connection with the pintle provided with a series of openings, and a coil spring provided with an extending end adapted for selective engagement with said openings.

10. In a hinge construction, a hinge member provided with a pintle, a coil spring carried upon and surrounding said pintle, a casing adapted to receive and support said pintle, the lower end of the hinge member adjacent its connection with the pintle provided with a series of openings positioned radially in respect to the pintle, and the coil spring provided with an extending end adapted for selective engagement with said openings.

11. In a hinge construction, a hinge member provided with a pintle, a coil spring surrounding said pintle, a casing adapted to receive and support said pintle, a hinge member provided with an enlarged portion adjacent one end of said pintle, said enlarged portion having an end extending to a point in front of the hinge member and having a series of openings radially disposed in respect to the pintle, the coil spring provided with an extending end adapted for selective engagement with said openings, and the casing provided at its lower end with an extending stop member positioned below and in front of the hinge member, whereby the extending stop member of the casing is adapted to be engaged by the extending portion of the hinge member.

12. In a hinge construction, a hinge member provided with a pintle, a casing adapted to receive and support said pintle, the hinge member provided with an extending portion extending to a point in front of the hinge member, and the casing provided at its lower end with an extending stop positioned

beneath the hinge member, whereby the extending portion of the hinge member is adapted to engage the stop of the casing upon the rotation of the hinge member.

- 5 13. In a hinge casing adapted to receive and rotatably support a hinge pintle, a bolt for fastening the upper end of said casing to a door frame or the like, and the lower end of said casing provided with an inwardly extending pin adapted for engage-

ment with an opening in said frame, whereby said casing is flexibly fastened to the frame in a manner to withstand both vertical and horizontal pressure by the use of one bolt.

15 In testimony whereof, we hereunto affix our signatures.

HENRY MOECKER, JR.
THEODORE THOMPSON.
